CONDENSER

Filed June 1, 1923

Patented May 14, 1929.

UNITED STATES PATENT OFFICE.

ARTHUR ATWATER KENT, OF ARDMORE, PENNSYLVANIA.

CONDENSER.

Application filed June 1, 1923. Serial No. 642,760.

My invention relates to electrical condensers, and more particularly variable condensers, of general application, and utilizable more particularly in radio circuits or systems.

It is the object of my invention to provide a condenser in which the movable system is easily and freely rotatable and which will nevertheless remain in position to which adjusted.

In accordance with my invention, the rotatable condenser plates are mounted upon a shaft which has a bearing, preferably conical, upon a resilient or spring member which exerts a force longitudinally of the shaft, thrusting it against a second bearing, preferably conical, the resilient or spring member serving also to effect good electrical contact with the moving system.

Further in accordance with my invention, I provide an end plate, base or top of molded insulating material, provided with means for supporting the aforesaid resilient or spring member, for supporting the stationary structure of the condenser, and for mounting the condenser as a whole upon a support, as a panel board.

My invention resides in structure and features of combination of the character hereinafter described and claimed.

For an illustration of one of the various forms my invention may take, reference is to be had to the accompanying drawing, in which:

Fig. 1 is a front elevational view of a panel board having attached thereto my condenser, with the operating handle in front of the panel board.

Fig. 2 is a vertical sectional view, some parts in elevation, taken on the line 2-2 of Fig. 1.

Fig. 3 is a horizontal sectional view, partly in plan, taken on the line 3-3 of Fig. 1.

Fig. 4 is a vertical sectional view, parts in elevation, taken on the line 4-4 of Fig. 2.

Fig. 5 is a fragmentary sectional view, partly in plan, taken on the line 5-5 of Fig. 4.

Fig. 6 is a fragmentary sectional view, partly in plan, taken on the line 6-6 of Fig. 1.

Fig. 7 is a perspective view of a spring member.

Referring to the drawing, 1 is a board or other support, as a panel board, upon which

the condenser structure may be mounted, though it will be understood that my invention is not limited to a condenser structure utilizable only for mounting upon panel boards, but that my structure may be utilized in any other suitable or desirable relation. The base, top or end plate 2 of the condenser structure is preferably molded of insulating material, a phenol condensation product, and the like, and has the integral circumferential flange or rim 3. Integral with the member 2 are molded a plurality of bosses 4, drilled and tapped to receive the screws 5, by which the member 2 and the condenser structure as a unit are secured to or supported upon the rear of the board or supporting member 1.

At preferably equidistant points circumferentially of the member 2, there are molded therein metallic inserts 6, into each of which is threaded a rod or post 7, on whose opposite end is threaded a hexagonal or other nut 8, into which is threaded a screw 9, between whose head and the nut 8 is confined the sheet metal member, bottom plate or end plate 10, of circular or any other suitable shape. Upon two adjacent rods or posts 7 are alternately disposed the fixed condenser plates 11, constituting the fixed armature of the condenser, and the washers 12, serving as spacers for maintaining uniform distances between the several condenser plates 11. The plates 11 and the washers 12 are tightly held between the insert 6 and the nut 8, threaded on the rod 7. Between the third insert 6 and nut 8, and surrounding the rod or post 7, is disposed the spacer tube 13, as indicated in Fig. 2.

In bosses 14, integral with the member 2, are molded the metallic inserts 15, into which are threaded screws 16, which extend through holes 17^a and hold at its ends the resilient or spring member 17, of sheet bronze or other suitable material, having struck up therefrom at its center the frusto-conical bearing member 18. Struck up from the same side of the member 17 are the integral resilient or spring tongues 19, whose ends are disposed opposite the adjusting screws or adjustable abutments 20, threaded through the member 2 and provided with lock nuts 21.

The shaft 22 has the conical bearing portion 23 bearing in the aforesaid bearing member 18, carried by the spring 17. Adjacent the bearing 23 is the shoulder 24 on the shaft 22, between which and the nut 25, threaded

on the end of shaft 22, alternate the movable condenser plates 26, constituting the movable armature of the condenser, and the spacer or separating washers 27, the washers and plates 26 being so positioned that the plates 26, when rotated by and with the shaft 22, interleave with the stationary condenser plates 11, without contacting therewith. The shaft 22 at its end is provided with a conical recess 28, serving as a bearing upon the conical end 29 of the screw 30 threaded through the block of insulating material 31, secured by screws 32 to the plate 10 and having a central boss or portion extending through a central opening in the plate 10. A nut 33, threaded upon the screw 30, serves to lock it in position to which it may be adjusted.

Accordingly, the movable system of the condenser, comprising the shaft 22, plates 26 and washers 27, has conical bearings at 23 and 29 upon the spring member 17 and screw 30, respectively. The spring 17 thrusts against the shaft longitudinally thereof at its conical bearing 23, forcing and holding the same against the conical bearing 29. The magnitude of this thrust or force is adjustable by adjusting the screws 20, thereby adjusting the tongues 19 to different positions, and thereby changing the tension or thrust 30 exerted by the spring 17. The shaft 22 has an extension 34, passing through the aperture 35 in the member 2 and through the aperture 35^a in the panel 1. At the front of the panel 1 is the operating handle or knob 36, preferably of molded insulating material, having a metallic insert 37 molded therein and receiving the shaft end 34. A set screw 38 serves to secure the knob 36 upon the shaft extension 34. Integral with the knob 36 40 is molded the dial 39, which may carry suitable scale markings co-acting with a stationary index 40 upon the panel 1. In a boss 41, integral with the member 2, is molded as an insert a pin or stub shaft 42, Fig. 6, 45 extending through an aperture 43 in the panel 1, and disposed adjacent the periphery of the bevelled dial rim 39. Rotatable upon the stub shaft 42 is the thumb wheel or button 44, having a recess 45 in which is disposed the 50 head of a screw 46 threaded into the shaft 42 and serving to prevent the member 44 from coming off the shaft 42. On its inner end the member 42 carries the ring or tire 47, of rubber or other suitable material, preferably bevelled at its end to contact with the bevelled rim 39 of the dial, the screw head 46 being so positioned that the member 44 and its ring 47 have sufficient play longitudinally of the shaft 42 for the ring 47 to be normally out 55 of contact with the rim 39.

In making an adjustment of the condenser, the knob 36 is grasped and turned, thereby rotating the condenser plates 26 with respect to the fixed condenser plates 11, until 60 their overlap is of such extent as to effect the

amount of capacity desired, the air intervening between the fixed and movable plates serving as dielectric.

To make the final adjustment with nicety, the hand is removed from the knob 36 and applied to the wheel or button 44, which is pressed in longitudinally of the shaft 42 to bring the shoe or ring 47 into engagement with the dial rim 39, and upon turning the wheel 44 the frictional engagement between 75 the ring 47 and rim 39 will cause rotation of the dial 39, and therefore of the movable structure of the condenser. Close or nice adjustment is thus effectable because the diameter of the shoe or ring 47 is small compared with the diameter of the dial rim 39, with the result that a considerable angular movement of the thumb wheel 44 effects but slight angular movement of the rotatable system of the condenser. 85

The fixed condenser plates 11 are all electrically connected to each other and through the washers 12 and rod 7, and nuts 8, with the plate 10, which may carry a binding screw or binding post for connecting the stationary 90 condenser plates in circuit. Similarly, the rotatable condenser plates 26 are all in electrical connection with each other and through the washers 27 and shaft 22, bearing members 23 and 18, and spring member 17, with 95 which latter may be connected a conductor for connecting the rotatable plates in circuit. The plate 17 may be connected by a conductor with a binding post carried upon the inner side of the base 2, such binding 100 post serving then for holding a conductor for connecting the movable condenser plates in circuit.

It is preferred that the bearing plate or member 17 may be shiftable or adjustable as 105 to its position, thereby adjusting or shifting the position of the bearing 18 for the shaft 22, thereby to adjust or position the movable armature plates 26 with respect to the stationary armature plates 11. For this purpose the holes 17^a, Fig. 7, through which the shanks of the screws 16 extend, may be large as compared to the diameter of the shanks of the screws 16, permitting adjustment of the plate 17, and therefore the bearing 18 110 and shaft 22, and the armature plates 26. After adjustment or suitable positioning of the member 17 has been effected, the screws 16 are tightened and hold the member 17 in the position to which adjusted. It may be 115 found in assembling a condenser of the character described that one or more of the plates 16 touches or too closely approaches a neighboring stationary plate 11, and consequently, by effecting adjustment of the plate or member 17 as described, that position of the shaft 22 may be found and fixed which will cause all the plates 26 freely to move between the stationary plates 11 without touching or too 120 closely approaching any of them. 130

What I claim is:

1. Condenser structure comprising a supporting member, a sheet spring member carried thereby, a bearing carried by said sheet spring member, a shaft rotatable on and extending through said spring member, and a condenser armature and an operating member carried by said shaft on opposite sides of said member.
2. Condenser structure comprising a supporting member, a sheet spring member carried thereby and spaced therefrom, said spring member having an integral conical bearing, a shaft having a conical portion rotatable in said bearing, and a rotatable condenser armature and an operating member carried by said shaft on opposite sides of said bearing.
3. Condenser structure comprising a supporting member, a spring member carried thereby, a bearing on said spring member, a tongue on said spring member, a shaft rotatable in said bearing, a rotatable condenser armature carried by said shaft, and an adjustable abutment engaging said tongue.
4. Condenser structure comprising a supporting member, a sheet spring member having an integral thrust bearing, a shaft extending through said member and having a portion supported by and rotating in said bearing and against which said bearing thrusts to rotatably support said shaft, and a rotatable condenser armature and an operating member carried by said shaft on opposite sides of said spring member.
5. Condenser structure comprising a supporting member, a sheet spring member having an integral thrust bearing, a shaft having a portion rotating in said bearing and against which said bearing thrusts, a rotatable condenser armature carried by said shaft, a tongue integral with said spring member, and an abutment engaging said tongue for determining the thrust upon said shaft.
6. Condenser structure comprising supporting members spaced from each other, a shaft having a conical portion, a sheet metal member having a conical bearing integral therewith, said bearing having an aperture, said shaft extending through and appreciably beyond said aperture and the conical portion on said shaft rotating in said conical bearing, and a thrust bearing for said shaft carried by another of said supporting members.
7. Condenser structure comprising supporting members spaced from each other, a shaft having a conical portion, a sheet metal spring having an integral conical bearing, said bearing having an aperture, said shaft extending through and appreciably beyond said aperture and the conical portion on said shaft rotating in said conical bearing, a thrust bearing for said shaft carried by another of said supporting members, and an abutment engaging said spring for adjusting the thrust upon said shaft.
8. Condenser structure comprising supporting members spaced from each other, a shaft having a conical portion, a sheet metal spring having an integral conical bearing, said bearing having an aperture, said shaft extending through said aperture and the conical portion on said shaft rotating in said conical bearing, a thrust bearing for said shaft carried by another of said supporting members, said spring having an integral tongue, and an abutment engaging said tongue.
9. Condenser structure comprising an end plate of molded insulating material, inserts molded in said end plate, a sheet spring secured to said inserts and spaced from said end plate, said spring having an integral conical bearing, a shaft having a conical portion rotating in said bearing and against which said spring thrusts, a rotatable condenser armature carried by said shaft, and an abutment carried by said end plate and engaging said spring.
10. Condenser structure comprising an end plate of molded insulating material, inserts molded in said end plate, a sheet spring secured to said inserts and spaced from said end plate, said spring having an integral conical bearing, a shaft having a conical portion rotating in said bearing and against which said spring thrusts, a rotatable condenser armature carried by said shaft, said spring having an integral tongue, and an abutment carried by said end plate engaging said tongue.
11. Condenser structure comprising a rotatable shaft, a condenser armature carried thereby, a co-acting condenser armature, a sheet spring member providing a bearing and through which said shaft extends, a conical bearing on said shaft engaging in said first named bearing, and an operating member on said shaft on the opposite side of said bearing from said first named armature.
12. Condenser structure comprising a sheet spring member having a bearing, a shaft having a portion supported by and rotating in said bearing and against which said bearing thrusts, a rotatable condenser armature carried by said shaft, tongues on said spring member and disposed on opposite sides of said bearing, and abutments engaging said tongues for determining the thrust of said bearing upon said shaft.
13. A variable condenser comprising a stator, a front end supporting plate and a rear end supporting plate, a rotor and means supporting the rotor in the end supporting plates including a spring-bearing supportingly carrying one side of the rotor and arranged between the rotor and the front end supporting plate, the said condenser having

a shaft projecting through said front end supporting plate.

14. A variable condenser comprising a stator, end supporting plates, a rotor and means supporting the rotor in the end supporting plates including a unitary spring-bearing supportingly carrying one side of the rotor, the said rotor having a shaft extending through said spring bearing.

15. A variable condenser comprising a stator, end supporting plates, a rotor having a tapered bearing seat and means supporting the rotor in the end supporting plates including a unitary spring-bearing supportingly carrying one side of the rotor, the bearing portion of the spring being tapered for mating with the rotor tapered bearing seat, the said rotor having a shaft projecting through said spring bearing.

16. Condenser structure comprising a supporting member, a sheet spring member carried thereby, an apertured conical bearing struck up from said spring member, a shaft

extending through the aperture of said conical bearing and having a conical portion rotatable in said conical bearing, a rotatable condenser armature carried by said shaft on one side of said spring member, and an operating member carried by said shaft on the opposite side of said spring member.

17. Condenser structure comprising a supporting member, a sheet spring member carried thereby, an apertured conical bearing on said spring member, a shaft extending through the aperture of said conical bearing and freely through said supporting member, a rotatable condenser armature carried by said shaft on the opposite side of said spring member from said supporting member, and an operating member carried by said shaft on the side of said supporting member opposite to said armature.

In testimony whereof I have hereunto affixed my signature this 29th day of May, 1923.

ARTHUR ATWATER KENT.
